BOAT

Filed July 28, 1925

WITNESS:

Patented July 6, 1926.

1,591,341

UNITED STATES PATENT OFFICE.

FRANK I. STILES, OF MIAMI, FLORIDA.

BOAT.

Application filed July 28, 1925. Serial No. 46,603.

This invention relates to a boat provided with a well whereby persons can see objects on the bottom of the body of water on which the boat floats, the general object of the invention being to provide means for keeping the surface of the water in the well still so as to prevent distortion of the vision by the effect of waves on the light rays.

Another object of the invention is to provide means for raising the above mentioned means off of the surface of the water to enable such means to be cleaned and to prevent said means from interfering with the progress of the boat through the water when said means are not being used.

Another object of the invention is to make the above mentioned means in the form of a frame having transparent plates therein with means for arranging the parts that air will be expelled from under the parts as the frame enters the water, thus preventing bubbles from occurring under the transparent parts, which would interfere with the vision.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a transverse sectional view through a boat provided with my invention.

Figure 2 is a similar view but showing the device in raised position.

Figure 3 is a plan view of the device.

Figure 4 is a detail view showing guiding means for the device.

Figure 5 is a detail sectional view on line 5—5 of Figure 3.

In these views, 1 indicates the well formed in the hull of the boat 2 so that objects on the bottom of the body of water in which the boat is floating can be observed by persons lined around the rail 3 which surrounds the well.

Vision of such objects is often distorted by waves on the surface of the water in the well, and in order to prevent these waves, I provide a frame 4, provided with transparent plates 5, which fits in the well and

rests upon the surface of the water therein. Thus the surface is kept smooth and the observers can look through the transparent plates 5 and see the objects without distortion. The frame is so formed that its bottom pieces and the plates 5 slope upwardly from the center so that as the frame enters the water air under the frame will pass outwardly from the sides thereof so that this air will not be trapped under the frame and cause air bubbles which would interfere with the vision of the observers. The air passes through the ports 6 formed in the lower edges of the frame. As will be seen, the frame is so made that it will float upon the water and water cannot reach the upper surfaces of the transparent plates.

I provide means for raising the frame so that the transparent members can be cleaned and so that the frame will not interfere with the movement of the boat through the water when said frame is not being used. Such means may be of any desired type, though the drawings show the well known block and tackles 7. After the frame is raised, strips 8 may be placed under the same and rest upon the railing 3, or any other suitable part of the boat, to relieve the cables from the weight of the frame. Any suitable means can be used for steadyng the frame when in its lowered position, such means being shown in the drawings as the projections 9 on the frame engaging the projections 10 on the walls of the well.

The glass or transparent part does not form a part of the bottom of the boat, as in glass bottom boats now in use, so that the breaking of the glass would in no wise endanger the boat. This transparent frame is only in the water when the bottom of the sea is being shown.

The drawing shows a boat as being built with a pair of pontoons 12, these being spaced apart to form the well and the well is inclosed by a cabin 13 which is constructed with the light excluding and ventilating means shown and described in my Patent No. 1,369,570, dated February 22, 1921.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In combination with a boat including spaced pontoons forming an observation well in the boat between the pontoons, a frame 5 supporting a plurality of transparent panels with the panels upon opposite sides of the center of the frame inclined toward

the center and the side edges of said frame at one side of the panels having air ports therethrough and means carried by the boat 10 for raising and lowering the frame in the well.

In testimony whereof I affix my signature.

FRANK I. STILES.
